RAGNAR CARLSTEDT, OF STOCKHOLM, SWEDEN

HYDRAULIC REGULATOR

Application filed October 25, 1930, Serial No. 491,128, and in Sweden April 8, 1929.

The present invention refers to hydraulic regulators operating with a non-compressible regulating liquid, such as water, oil or the like, in which the throttled pressure liquid actuates a piston or diaphragm or the like pertaining to a servo-motor, and continues through a discharge opening controlled by an impeding member which is actuated by the condition to be controlled.

10 The invention relates to a member effecting the throttling of the regulating liquid, and consists essentially in that said member comprises a regulating valve provided between the supply conduit and the discharge conduit and communicating with the conduit leading to the servo-motor, in order to facilitate draining of the servo-motor as well as scavenging of the channels for the regulating liquid.

20 The throttle member, which is preferably arranged with respect to the valve casing so as to be removable from the outside thereof, may advantageously be so constructed and arranged that, when the same is adjusted, 25 connection will in the first instance be established between the servo-motor and the discharge conduit, for the purpose of draining the servo-motor, while on a continued movement of the member, direct connection is further established between the supply conduit and the discharge conduit for the regulating liquid, for scavenging purposes. Thus quick draining and scavenging is ensured even during the operation of the device. The end of the throttle member opening into the supply conduit is preferably 35 conical, with the cross-sectional area of the passage increasing in the direction of flow, so that jamming in the throttle member of extraneous particles entrained with the regulating liquid is prevented.

The accompanying drawings illustrate an arrangement embodying this invention. Fig. 1 is a longitudinal section of servo-motor of known type provided with a throttle member according to the invention. Figs. 2 and 3 are longitudinal sections on a larger scale of the valve casing with the throttle member, viewed in two directions 50 at right angles to each other.

In Fig. 1, the cylinder pertaining to the servo-motor is designated by 1, the working piston being denoted by 2 and the piston rod by 3. The supply of the regulating liquid takes place through a channel 4, Fig. 2, provided with a contracted passage 5 in which is arranged a cleansing needle 6 to prevent said passage 5 from being stopped up. The supply to the cylinder 1 takes place through a channel arrangement 4¹ opening at a point 55 situated on the side of the working piston 2 opposite to that of the piston rod 3.

Rotatably arranged at the free end of the piston rod is a cord pulley 7 having a cord 8 running thereover, one end of which is secured at the bottom of the cylinder, while its other end cooperates with a member to be adjusted, such as a steam valve.

Formed in the cover 9 of the cylinder 1 is a chamber 10 containing a bellows 11 70 adapted to actuate a regulating lever 14 pivotally attached to the upper side of the cylinder, by means of a rod 12 provided with a knife edge, against the action of a spring 13. Lever 14 is provided at its free end with a pin 15 having a plane lower side bearing against a ball 17 which is freely movable in a sleeve-like member 16, said ball 17 regulating the discharge of the pressure liquid through a nozzle opening 18.

80 The issuing liquid escapes through the passage 19 in the housing or casing 20 and through the discharge pipe 21. To deflect the liquid issuing through the opening 18 downwards to the passage 19, the pin 15 connected with the regulating lever 14 has a cap 22 secured thereto, said cap being freely movable in a corresponding opening in the casing 20.

85 The throttle member consists, in the embodiment shown, of a sleeve-like member 24 screwed into the casing 20 and provided with a handle 23, in which member 24 the above mentioned contracted passage 5 is arranged at the end 25 of the member opening into the supply conduit 4. Said end portion is 90 conical, and the cross-sectional area of the passage increases in the direction of flow, so that jamming of extraneous particles of the regulating liquid is avoided. The liquid entering the sleeve-like member 24 through 95 100

the passage 5 is discharged through openings 26 in the wall of the sleeve to the channel arrangement 4¹ leading to the servo-motor 1, 2 and the nozzle opening 18.

5 Between said channel 4¹ and the outlet passage 19 is provided an opening 27, Fig. 2, adapted to be regulated by means of the throttle member 24 formed into a valve. This throttle member is, for the said purpose, provided with a conical enlargement 28 adapted in the position shown to tighten against a corresponding seat at the mouth of the opening 27. The front portion of the member 24 is cylindrical and fits tightly into 15 a corresponding opening 29 in the casing 20.

When the member 24 is screwed out, connection is in the first instance established between the channel arrangement 4¹ and the outlet passage 19 through the opening 27, 20 and tapping of the servo-motor is effected. When the member 24 is screwed further out, the opening 29 is made free and scavenging takes place. Both of these operations may, if desired, be performed while the device is 25 active. When required, the member 24 may be entirely removed from the casing 20 for inspection or exchange.

The cleansing needle 6 for the passage 5 extends centrally through the throttle member 24 and may be removed together with the latter or independently thereof.

The mode of operation of the device is previously known per se and requires no further discussion here. On alterations of the 35 condition which is to be kept constant by means of a device of the type in question, for instance of the steam in a steam conduit, the pressure is altered in the chamber 10 and, consequently, the position of the regulating lever 14 is altered through the bellows 11 and the rod 12, so that pressure liquid will be discharged through the nozzle opening 18 to a greater or smaller extent, corresponding pressure variations being thus 40 produced in the servo-motor which, in turn, actuates a steam valve, for example, in a corresponding degree.

What I claim is:—

1. A hydraulic regulator comprising a 50 servo-motor operating with a non-compressible regulation liquid, a movable member, such as a piston, diaphragm or the like, pertaining to said servo-motor and actuated by said regulation liquid, an impeding member 55 controlling the discharge of said liquid from said servo-motor and actuated by the condition which is to be controlled, a housing, a supply conduit for said regulation liquid leading to said housing, a discharge conduit 60 for said liquid leading from said housing, a conduit for said liquid leading from said housing to said servo-motor, and a throttling member in said housing for throttling the regulation liquid before it enters the servo- 65 motor, said throttling member forming a

regulation valve arranged between said supply conduit and said discharge conduit and forming a communication between said supply conduit and the conduit leading to the servo-motor, so as to facilitate draining of 70 the servo-motor as well as scavenging of said conduits, and said throttling member being further so secured to said housing as to be removable from the outside thereof.

2. A hydraulic regulator comprising a 75 servo-motor operating with a non-compressible regulation liquid, a movable member, such as a piston, diaphragm or the like, pertaining to said servo-motor and actuated by said regulation liquid, an impeding member 80 controlling the discharge of said liquid from said servo-motor and actuated by the condition which is to be controlled, a housing, a supply conduit for said regulation liquid leading to said housing, a discharge conduit, 85 for said liquid leading from said housing, a conduit for said liquid leading from said housing to said servo-motor, a throttling member in said housing for throttling the regulation liquid before it enters the servo- 90 motor, said throttling member forming a regulation valve arranged between said supply conduit and said discharge conduit and forming a communication between said supply conduit and the conduit leading to the servo- 95 motor, so as to facilitate draining of the servo-motor as well as scavenging of said conduits, and said throttling member being further so secured to said housing as to be removable from the outside thereof, and a cleansing 100 member removably secured to and arranged in said throttling member.

3. A hydraulic regulator comprising a servo-motor operating with a non-compressible regulation liquid, a movable member, 105 such as a piston, diaphragm or the like, pertaining to said servo-motor and actuated by said regulation liquid, an impeding member controlling the discharge of said liquid from 110 said servo-motor and actuated by the condition which is to be controlled, a housing, a supply conduit for said regulation liquid leading to said housing, a discharge conduit for said liquid leading from said housing, a conduit for said liquid leading from said 115 housing to said servo-motor, and a throttling member in said housing for throttling the regulation liquid before it enters the servo-motor, said throttling member forming a regulation valve arranged between said supply 120 conduit and said discharge conduit and forming a communication between said supply conduit and the conduit leading to the servo-motor, so as to facilitate draining of the servo-motor as well as scavenging of said 125 conduits, and said throttling member being further so secured to said housing as to be removable from the outside thereof and being so constructed that when adjusted a communication will first be established between 130

the servo-motor and said discharge conduit, while on a continued adjustment of said member a direct communication will be established between said supply conduit and said discharge conduit.

4. A hydraulic regulator comprising a servo-motor operating with a non-compressible regulation liquid, a movable member, such as a piston, diaphragm or the like, pertaining to said servo-motor and actuated by said regulation liquid, an impeding member controlling the discharge of said liquid from said servo-motor and actuated by the condition which is to be controlled, a housing, a supply conduit for said regulation liquid leading to said housing, a discharge conduit for said liquid leading from said housing, a conduit for said liquid leading from said housing to said servo-motor, a throttling member in said housing for throttling the regulation liquid before it enters the servo-motor, said throttling member forming a regulation valve arranged between said supply conduit and said discharge conduit and forming a communication between said supply conduit and the conduit leading to the servo-motor, so as to facilitate draining of the servo-motor as well as scavenging of said conduits, and said throttling member being further so secured to said housing as to be removable from the outside thereof and being so constructed that when adjusted a communication will first be established between the servo-motor and said discharge conduit, while on a continued adjustment of said member a direct communication will be established between said supply conduit and said discharge conduit, and a cleansing member removably secured to and arranged in said throttling member.

5. A hydraulic regulator comprising a servo-motor operating with a non-compressible regulation liquid, a movable member, such as a piston, diaphragm or the like, pertaining to said servo-motor and actuated by said regulation liquid, an impeding member controlling the discharge of said liquid from said servo-motor and actuated by the condition which is to be controlled, a housing, a supply conduit for said regulation liquid leading to said housing, a discharge conduit for said liquid leading from said housing, a conduit for said liquid leading from said housing to said servo-motor, and a throttling member in said housing for throttling the regulation liquid before it enters the servo-motor, said throttling member forming a regulation valve arranged between said supply conduit and said discharge conduit and forming a communication between said supply conduit and the conduit leading to the servo-motor, so as to facilitate draining of the servo-motor as well as scavenging of said conduits, and said throttling member being further so secured to said housing

as to be removable from the outside thereof, the passage of said throttling member at the end thereof directed towards said supply conduit having an increasing cross-sectional area in the direction of flow of the regulation liquid so as to prevent jamming in said member of extraneous particles entrained with the regulation liquid.

6. A hydraulic regulator comprising a servo-motor operating with a non-compressible regulation liquid, a movable member, such as a piston, diaphragm or the like, pertaining to said servo-motor and actuated by said regulation liquid, an impeding member controlling the discharge of said liquid from said servo-motor and actuated by the condition which is to be controlled, a housing, a supply conduit for said regulation liquid leading to said housing, a discharge conduit for said liquid leading from said housing, a conduit for said liquid leading from said housing to said servo-motor, a throttling member in said housing for throttling the regulation liquid before it enters the servo-motor, said throttling member forming a regulation valve arranged between said supply conduit and said discharge conduit and forming a communication between said supply conduit and the conduit leading to the servo-motor, so as to facilitate draining of the servo-motor as well as scavenging of said conduits, and said throttling member being further so secured to said housing as to be removable from the outside thereof, and a cleansing member removably secured to and arranged in said throttling member, the passage of said throttling member at the end thereof directed towards said supply conduit having an increasing cross-sectional area in the direction of flow of the regulation liquid, so as to prevent jamming in said member of extraneous particles entrained with the regulation liquid.

7. An arrangement according to claim 1 characterized by the end of the throttling member directed towards the supply conduit for the regulation liquid being conical.

8. An arrangement according to claim 5 characterized by the end of the throttling member directed towards the supply conduit for the regulation liquid being conical.
